(57) **CLAIM**

The ornamental design for a wet wipe packet as shown and described.

DESCRIPTION

FIG. 1 is a top perspective view of a wet wipe packet comprising the new design;

FIG. 2 is a top view of the design of FIG. 1;

FIG. 3 is a bottom view of the design of FIG. 1;

FIG. 4 is a front elevational view of the design of FIG. 1;

FIG. 5 is a back elevational view of the design of FIG. 1;

FIG. 6 is a left elevational view of the design of FIG. 1; and,

FIG. 7 is a right elevational view of the design of FIG. 1.

1 Claim, 4 Drawing Sheets
